(57) **CLAIM**

The ornamental design for a head wearable light therapy device, as shown and described.

DESCRIPTION

FIG. 1 is a front perspective view of a head wearable light therapy device in accordance with the present invention;

FIG. 2 is a left side view thereof;

FIG. 3 is a right side view thereof;

FIG. 4 is a front view thereof;

FIG. 5 is a rear view thereof;

FIG. 6 is a top view thereof; and,

FIG. 7 is a bottom thereof.

The broken lines in the form of a human head depict environmental subject matter and form no part of the claim thereof. All the other broken lines shown in the drawings depict portions of the head wearable light therapy device that form no part of the claimed design.

1 Claim, 5 Drawing Sheets
